Primary Examiner—Alan P. Douglas*Assistant Examiner*—Robert M. Spear*Attorney, Agent, or Firm*—Bachman & LaPointe[57] **CLAIM**

The ornamental design for a side vented lid, as shown and described.

DESCRIPTION

FIG. 1 is a top plan view of one embodiment of a side vented lid showing my new design;

FIG. 2 is a bottom plan view thereof;

FIG. 3 is a side elevational view thereof showing the side vent;

FIG. 4 is an elevational view of the opposite side of the showing of FIG. 3;

FIG. 5 is an elevational view of the right side and left side of FIG. 1 thereof, the right side being a mirror image of the left side;

FIG. 6 is a top plan view of a side vented lid showing another embodiment of my new design;

FIG. 7 is a bottom plan view thereof;

FIG. 8 is a side elevational view thereof showing the side vent;

FIG. 9 is an elevational view of the opposite side of the showing of FIG. 8; and,

FIG. 10 is an elevational view of the right and left sides of FIG. 6 thereof, the right side being a mirror image of the left side.

The broken line showing of a glass receptacle is for illustrative purposes only and forms no part of the claimed design.
